SUPERREGENERATIVE RECEIVER

William Spencer Percival, Ealing, London, England, assignor to Electric & Musical Industries Limited, Hayes, Middlesex, England, a company of Great Britain

Application November 17, 1936, Serial No. 111,231
In Great Britain November 20, 1935

10 Claims. (Cl. 250—20)

The present invention relates to wireless and like receivers, and more particularly to receivers of the kind in which use is made of the principle of super-regeneration.

5 A known super-regenerative receiver comprises a thermionic valve having its anode circuit coupled back to its control grid circuit, the nature and magnitude of the back-coupling being such that an oscillation applied to the control grid 10 circuit tends to build up in amplitude; the valve is also arranged to generate "quenching" oscillations, which serve to quench the oscillations which build up in the input circuit, so that the valve generates trains of oscillations of the frequency 15 to which the input circuit is resonant, the trains occurring at the quenching frequency; the valve is arranged to operate as a detector, and if the applied oscillation is amplitude modulated, the modulation frequencies appear in the anode circuit. 20

Such a super-regenerative circuit, although the amplification of which it is capable may be high, is found to have grave disadvantages; more particularly, it is very susceptible to carrier wave 25 interference, and the level of noise (due, for example, to the Schrott and Johnson effects) is high, both these faults being due to lack of selectivity. Furthermore, in cases in which it is necessary to use a high quenching frequency, for example, in the case of the reception of television signals, it may be found that the amplification of the circuit is undesirably low. It has also been found that the power output at the modulation frequency from a circuit such as that described 30 is also low, that is to say, the valve operates inefficiently as a detector.

It is an object of the present invention to provide an improved wireless or like receiver of the super-regenerative type, in which the disadvantages mentioned above are reduced.

According to one feature of the invention, for the purpose of improving selectivity, a super-regenerative receiver is provided, comprising a valve including a cathode, control grid and anode and 45 having a resonant circuit associated with its control grid circuit and with its anode circuit coupled to its control grid circuit in such a manner that a positive feed back can occur and a source of quenching oscillations, the arrangement being 50 such that for a considerable portion of a cycle of the quenching oscillations the effective selectivity of said resonant circuit has a value not greatly different from that corresponding to the condition in which the dynamic resistance of the 55 resonant circuit is substantially infinite. In other

words the effective resistance of the resonant circuit for a considerable portion of a cycle of the quenching oscillations is at a minimum and hence the selectivity of the circuit is considerably increased. The circuit during this period thus permits the signal to build up at its own frequency when the resonant circuit is at substantially optimum selectivity, thus providing discrimination against noise and interference. The desired result may be achieved by suitably choosing the magnitudes of the positive feed-back and of the amplitude of the quenching oscillations. 5

Preferably, however, the source of quenching oscillations is arranged to generate trains of oscillations of a wave form such that in the interval 15 between a quenching period and the subsequent burst of oscillation the amplitude of the quenching oscillation has a value corresponding closely to critical reaction for a time which is a substantial portion of a cycle of the quenching oscillation. By critical reaction is meant the condition in which the dynamic resistance of the input resonant circuit is infinite, and the circuit resistance during such conditions may be substantially zero, or even slightly negative. Suitable wave 20 forms for the quenching oscillation will be described hereinafter. 25

For the purpose of improving the power output from a super-regenerative valve the quenching frequency oscillations are given a wave form such that between a burst of oscillation and the subsequent quenching period the amplitude of the quenching oscillation has a value corresponding closely to critical reaction for a time which is a substantial portion of a cycle of the quenching 30 oscillation. 35

In order to improve amplification, the present invention provides a super-regenerative receiver comprising two thermionic valves in cascade, each having a cathode, control grid and an anode and 40 an additional electrode or electrodes if desired, and means for feeding back energy derived from the output circuit of the second valve to the input circuit of the first valve in the positive sense, and means whereby the two valves are separately 45 quenched. In such an arrangement, more than one resonant circuit will normally be provided, in which case it is necessary to damp both of the tuned circuits. If the natural damping of these circuits is not sufficient, diodes may be provided, one for each circuit which are caused to pass currents and hence to damp the circuits during the quench period. 50

The trains of oscillation generated in the super-regenerative stage of a receiver according to the 55

invention are preferably applied, to a separate detector, which is preferably constituted by a diode valve of the low impedance type, and from which modulation frequency oscillations can be derived.

It has been found that the voltage across the resonant circuit associated with the super-regenerative valve contains not only a carrier of the original frequency with its own modulation, but also the original carrier frequency modulated with the quench frequency, which in turn is modulated with the original modulation.

Hence according to a further feature of the invention, the voltage developed across the resonant circuit is applied to a separate first detector, and the modulated quench frequency component, which is derived from the first detector, is applied (after amplification if desired) to a second detector, from which the modulation-frequency component is derived.

In an arrangement such as that last described, embodying two detectors, the efficiency of the second detector, and the quality of its output, may be improved by feeding quenching frequency oscillations thereto in suitable phase; the second detector may, in such an arrangement, be arranged to operate as a form of homodyne detector.

The chief advantage arising from the use of a separate detector is that owing to the low impedance of its input circuit to frequencies other than the original carrier frequency only this frequency and the carrier modulated by the quench frequency will be applied thereto and hence for example, the quench frequency is prevented from passing to the subsequent amplifiers. Furthermore the wave form of the high frequency oscillations exhibits sharp peaks, and hence a rectifier of the low impedance diode type is more efficient. Again, where the modulation frequency output is taken from the super-regenerative valve several stages of low frequency amplification are often necessary and as its well known low frequency amplification tends to introduce hum and instability. Where, however, two detector stages are used, the whole or a part of the desired amplification can take place at high frequencies. Where two detectors are employed with the first detector followed by a resonant circuit tuned to the quenching frequency it has been found that the modulation frequency output of the second detector is frequently greater than the output that can be obtained from the first detector at the same frequency. A further advantage of using double detection is that a quenching frequency amplifier can be introduced between the two detectors, thus increasing the available voltage to the second detector and increasing its linearity and power output.

In order that the said invention may be clearly understood and readily carried into effect the same will now be more fully described with reference to the accompanying drawing in which:

Fig. 1 shows a super-regenerative receiver according to the invention.

Fig. 2 illustrates various wave forms which the quenching oscillations may have, and

Fig. 3 illustrates a modified form of super-regenerative stage according to the invention.

Referring to Fig. 1, an inductance coil 1 has one end 2 grounded, and the other end 3 thereof connected to a receiving aerial and is tuned by a variable condenser 4. The cathode of a triode valve 5 is connected to a point 6 in coil 1, and the control grid of valve 5 is connected to a point 7

therein through a condenser as shown. The anode of valve 5 is connected through a radio-frequency choke coil 8 and a filter resistance 9, with which are associated by-pass condensers 10 and 11, to the positive terminal 12 of a source 5 of anode current, not shown.

Valve 5 serves, in a manner which will be described hereinafter, as a super-regenerative valve, and quenching oscillations are derived from a valve 13, the anode of which is connected, through the primary winding of a transformer 14, to the positive terminal 12 of the anode current source. The cathode of valve 13 is grounded, and its control grid is connected to ground through a grid condenser 15 and the secondary winding of transformer 14. The latter winding is shunted by a condenser 16, and by a circuit comprising a condenser 17 and a potentiometer 18 in series. Grid condenser 15 has a leak resistance 19, and the valve 13 operates as a relaxation oscillation generator of the "blocking oscillation" type, which type is known in television technique. In the operation of valve 13 and its associated circuit the grid condenser 15 is charged by the flow of grid current from the valve to such an extent, during the first half cycle of oscillation, that further oscillation becomes blocked. The charge of condenser 15 leaks away through resistance 19 at a relatively slow rate until the grid potential reaches such a value that sufficient anode current flows again for oscillations to recommence. This action gives rise to positive pulses of potential across the grid coil of the transformer 14 at a frequency determined by the values of the condenser 15 and resistance 19 35 and the potential of the direct current source in the anode circuit. By means of a high pass filter constituted by the condenser 17 and potential divider resistance 18 a wave form of the kind shown in Fig. 2b is applied to the grid of the 40 valve 5 superposed on the bias voltages determined by the potentiometer 20. Other forms of oscillators in which the flow of current is periodically blocked may be employed if desired in association if necessary with suitable forms of high 45 pass or other filters. In the form shown in Fig. 1 of the drawing the circuits 17, 18, 20, 22, and 25 function as a high pass filter and the first of these components may have the value 0.0002 microfarad and the second component 50 50,000 ohms, the condenser 15 may have a capacity of 0.002 microfarad, the resistance 19 a value of 50,000 ohms, and the condenser 16 a capacity of 0.002 microfarad. Instead of employing a relaxation or blocking oscillator for 55 obtaining the desired wave form, a multivibrator system may be employed which may, if desired, be associated with a high pass or similar filter for generating the preferred wave form. Wave forms suitable for use in the invention will be 60 hereinafter more particularly referred to.

The control grid of valve 5 is given an adjustable negative bias from a tapping point on a potentiometer 20 associated with a source 21 of bias potential, through resistance 25. Quenching oscillations of the form shown in Fig. 2b are applied to valve 5 as aforesaid from an adjustable tapping point on potentiometer 18 through condenser 22 and radio-frequency choke coil 23 in 70 series, a high frequency by-pass condenser 24 being connected as shown.

As previously stated the cathode and grid of valve 5 are tapped into the aerial tuning circuit 1, 4, at points 6 and 7 and the valve then operates 75

to generate oscillation at the frequency to which this circuit is tuned.

By arranging that for a considerable portion, for example a third or more of the cycle of quenching oscillations, the wave form of the quenching oscillations has a substantially flat portion which is arranged to correspond with critical reaction the effective selectivity of the circuit is greatly increased since during this portion the effective resistance of the circuit is substantially zero.

Three suitable wave forms for affording this condition are shown at *a*, *b* and *c* in Fig. 2; in each case, the amplitude of the oscillation is plotted against time as abscissae, and parts of the oscillations above the abscissae correspond to burst of oscillation in the super-regenerative valve, while during the parts below, the super-regenerative valve is quenched. In Fig. 2*a*, which represents an ideal wave form, the parts *d* are arranged (for example in the case of the receiver of Fig. 1, by adjustment of the bias of valve 5 and hence of the amount of reaction) to correspond to critical reaction. Fig. 2*b* shows, as already stated, the wave form of the oscillation generated by a practical quench frequency oscillator.

In a receiver, using a quench wave form of the kind illustrated in Fig. 2*b* and operating at 44 megacycles per second, it was found possible to obtain a selectivity corresponding to a pass band of 100 kilocycles, with a gain of from 300 to 1000 times greater than that obtainable from an ordinary detector with critically adjusted reaction. It was also found that sensitivity could be adjusted by varying the amplitude of the quenching input by potentiometer 18, the reaction control (potentiometer 20) being left at a fixed adjustment thus maintaining selectivity at a high value. A suitable quenching frequency was found to be one between about 10 and 80 kilocycles per second.

In Fig. 2*c* is illustrated a wave form which may be employed if it is desired to increase the power output of the super-regenerative valve; the wave form includes, in addition to the parts *d* of Fig. 2*a*, further parts *e*, one of which follows each train of oscillation in the super-regenerative valve, and enables the signal to persist for a short time before it is quenched. The parts *e* are shown as corresponding to critical reaction, but they may if desired correspond to a condition of rather less reaction; in either case, these parts of the wave form result in an improvement in the load factor of the super-regenerative valve, that is, the ratio of the fraction of the operating time during which that valve is loaded to the maximum desirable load. The parts *d* of the wave form of Fig. 2*c* may be omitted if desired.

The upper end 3 of coil 1 is connected through condenser 26 to the anode of a diode 27, the cathode of which is earthed; the trains of oscillation from valve 5 are thus applied to, and are detected by, diode 27. The latter is shunted by a radio-frequency choke coil 28 in series with a circuit comprising a condenser 29 and an inductance coil 30 in shunt, tuned to the quenching frequency.

The oscillations at the quenching frequency are amplified by means of a high-frequency amplifier valve 31 which has a grid leak 32 and grid condenser 33, and has a resonant circuit 34 tuned to the quenching frequency arranged in its anode circuit. Potential differences set up across circuit 34 are fed through condenser 35 to the

anode of a second diode detector valve 36, the cathode of which is earthed. The diode 36 is connected through a quench frequency choke coil 37 to its load resistance 38; across which modulation frequency potential differences are established and which are fed through a filter 39 to the control grid of a low-frequency amplifier valve 40.

The output of detector 27 is found to consist of substantially saw-tooth oscillations of the quenching frequency, these oscillations being modulated with the modulation of the received signal, and disappearing when no signal is being received. Amplifier 31 is accordingly not loaded when no signal is present.

Certain features of the invention can be employed without utilising the wave forms shown in Figures 2*a*, 2*b* and 2*c*. For example the valve 13 may generate quenching oscillations of sinusoidal wave form, in which case means are preferably provided for adjusting the amplitude of the quenching oscillations applied to the super-regenerative valve to a value such that, over a substantial part of the quenching cycle, conditions of approximately critical reaction exist in the super-regenerative valve.

Reference is now directed to Fig. 3, in which is illustrated a modified form of super-regenerative stage according to the invention. A screen grid valve 41 has a resonant circuit comprising an inductance coil 42 and a variable condenser 43 connected in shunt arranged in its control grid circuit. The anode of valve 41 is connected through a further resonant circuit comprising an inductance coil 44 in shunt with a variable condenser 45 to the positive terminal 46 of a source (not shown) of anode current, the negative terminal of which is earthed; in operation, both resonant circuits are tuned to a wanted signal frequency.

The anode of valve 41 is coupled through a condenser 47 to the control grid of a further screen grid valve 48, the anode of which is connected through a radio-frequency choke coil 49 to the positive terminal 46 of the anode current source. The control grids of valve 41 and 48 are biased by means of biasing resistances 50 and 51 respectively.

The anode of valve 48 is connected through a condenser 52 both to one of two output terminals 53 and to the control grid of valve 41. Terminals 53 may be connected to a detector (not shown) such as detector 27 of Fig. 1, and the connection to the control grid of valve 41 serves to provide reaction.

Quenching oscillations of any suitable wave-form and amplitude are applied from source 54 to the control grids of valves 41 and 48 through radio frequency chokes 55 and 56 respectively; in this way, both valves 41 and 48 are separately quenched. The two resonant circuits 42, 43 and 44, 45 are arranged to have such damping that they are self-quenching when valves 41 and 48 are quenched; in other words, the damping is such that the oscillations which build up in these circuits die away sufficiently quickly during the quenching periods. Additional damping may be provided if desired by means of thermionic discharge devices arranged in shunt with the tuned circuits and made conductive, during quenching periods, by the quenching oscillations.

As is well known (see, for instance, the textbook "Wireless Principles and Practice" by L. S. Palmer, 1928 edition, pages 357-8) the amplification of a super-regenerative receiver is of

the form ae^B wherein B is a factor which is large as compared to unity and proportional to the mutual conductance of the valve. When an ordinary high frequency amplifier stage is employed, the factor a only is increased, but where two valves are employed in cascade as shown in Fig. 3, the factor B is approximately squared and although there is some reduction in the factor a this is relatively unimportant. Hence the arrangement in accordance with this feature of the invention is capable of making the best use of two valves from the point of view of amplification, particularly if the factor B is large as, for example, 6 or more.

15 The invention is not to be limited to the specific details described, as many modifications can be made within the spirit and scope of the appended claims.

I claim:

20 1. In a super-regenerative receiver an electronic tube including a cathode, control grid and anode, external connections between said tube elements forming an anode circuit and a control grid circuit, a resonant circuit associated with said control grid circuit, means for coupling the anode circuit to the control grid circuit in such a manner that a positive feed back can occur, a source of quenching oscillations, said source of quenching oscillations being provided with means for generating trains of oscillations of a wave form such that between a burst of oscillation and the subsequent quenching period the amplitude of the quenching oscillation has a value corresponding closely to 35 critical reaction for a time which is a substantial portion of a cycle of the quenching oscillation.

2. In a super-regenerative receiver, a first thermionic tube having an input circuit and an output circuit, a second thermionic tube having an input circuit and an output circuit, means for connecting the output circuit of the first tube to the input circuit of the second tube, means for feeding back energy derived from the output circuit of the second tube to the input circuit of said first tube in a positive sense, a source of quenching oscillations, coupling means between the source of quenching oscillations and each of said tubes for applying the quenching oscillations to each of said tubes and thereby separately quench each thereof.

3. In a receiver of the super-regenerative type, an electronic tube provided with an anode, a cathode and a grid electrode, external circuits connecting said tube electrodes so as to produce regeneration in the operation of said tube, a signal energy interceptor coupled to one of said circuits, a resistive voltage dividing circuit, means for applying a substantially constant potential across said last named circuit, a contact selectively movable over said circuit, means for connecting said grid electrode to said contact, a second resistive voltage dividing circuit, a source of quenching frequency for the receiver comprising, a relaxation oscillation generator of the blocking oscillation type, means for applying the quenching frequency energy across said second resistive voltage dividing circuit, a contact selectively movable over said last named circuit, 70 and means for connecting said grid electrode to said contact.

4. In a super-regenerative receiver, an electronic tube provided with an anode, a cathode and a grid electrode, external circuits connecting said electrodes so as to produce sufficient

regeneration in the operation of said tube to cause the generation of oscillations, a tunable circuit coupled with said external circuits for controlling the frequency of the generated oscillations, a signal energy interceptor coupled to the tunable circuit, means for biasing the grid electrode with respect to the cathode comprising a connection between the grid electrode and the cathode, said connection including a source of potential and a variable resistance, a source of quenching frequency for said receiver comprising, a relaxation oscillation generator, a voltage dividing circuit, means for applying the quenching frequency energy across said last named circuit and means including a condenser 15 for connecting the grid electrode of said tube to a point of said voltage dividing circuit.

5. In a super-regenerative receiver, an electronic tube provided with an anode, a cathode and a grid electrode, external circuits connecting the tube elements so as to produce oscillations, a tube circuit coupled with said external circuits for controlling the frequency of the generated oscillations, a signal energy circuit coupled to the tunable circuit, means for biasing the grid 25 of said tube with respect to the cathode thereof, a source of quenching frequency for said receiver comprising an oscillation generator including an electronic tube, a voltage dividing circuit, means for applying the quenching frequency oscillations across said last named circuit, a connection between the grid electrode of said first named tube and a point of said voltage dividing circuit, a diode rectifier for said receiver having an input side and an output side, means 35 for connecting the input side across said tunable circuit, a tunable circuit tuned to the frequency of the quenching oscillations, means including a radio frequency choke coil for connecting said last named tuned circuit across the output side 40 of said diode rectifier, an amplifier circuit for amplifying the output of the diode rectifier and a second rectifier connected across the output of said amplifier, and a utilizing circuit connected across the output of the last named rectifier. 45

6. In the operation of a super-regenerative receiver of the type which is provided with an oscillation generator circuit, including a regeneratively connected tube, tunable to oscillate at any signal frequency within a band of frequencies 50 and in which the generation of oscillations is intermittently quenched by application thereto of quenching oscillations of predetermined frequency during operation of the circuit, the method of greatly increasing the effective selectivity of the receiver which consists in controlling the wave form of the quenching oscillations so that during substantially a third of the cycle of the quenching oscillations the wave form thereof has a substantially flat portion which is 60 arranged to keep the tube during this interval at critical reaction.

7. In a super-regenerative receiver, an electronic tube provided with an anode, a cathode and a grid electrode, external circuits connecting the tube elements so as to produce positive regeneration causing generation of oscillations, a tunable circuit coupled with said external circuits for controlling the frequency of the generated oscillations, a signal energy interceptor 70 coupled to the tunable circuit, means for biasing the grid electrode of the tube with respect to the cathode thereof comprising a connection between the grid electrode and the cathode, said connection including a source of bias potential in series 75

with a variable resistance element, a source of quenching frequency for said receiver comprising a relaxation oscillation generator, a voltage dividing circuit, means for applying the quenching frequency oscillations across said last named circuit, a contact selectively movable over the last named circuit, means including a reactive device for connecting the grid electrode to the contact, a diode rectifier for said receiver and 10 means including a coupling capacity for connecting the diode rectifier across said tunable circuit.

8. In a super-regenerative receiver, an electronic tube provided with a cathode, a control grid and an anode, external connections between 15 said tube elements forming an anode circuit and a control grid circuit, a resonance circuit coupled with said control grid circuit, means for coupling the anode circuit to the control grid circuit in such a manner that positive feed-back can occur,

20 a source of quenching oscillations, said source of quenching oscillations being provided with means for controlling the generated quenching oscillations so that the trains of oscillations are of a wave form such that between a burst of 25 oscillation and the subsequent quenching period of the receiver the amplitude of the quenching oscillation has a value corresponding closely to critical reaction for a time which is a substantial portion of a cycle of the quenching oscillation.

30 9. The method of amplifying varying electric currents which includes the steps of impressing the varying potential of the current to be ampli-

fied upon a feedback system, generating a train of oscillations the wave form of which have a substantially flat portion over a substantial part of each cycle thereof, periodically damping the feedback system by applying the generated train of oscillations thereto whereby the varying electric currents and the generated oscillations are effectively combined, detecting the resulting energy, deriving therefrom energy of the quenching frequency modulated by a component of the 10 varying electric currents, amplifying the derived energy and detecting the amplified energy to derive therefrom the amplified varying electric currents.

10. In a super-regenerative receiver, a first 15 thermionic tube having an input circuit and an output circuit, a second thermionic tube having an input circuit and an output circuit, means for electrically connecting the output circuit of the first tube to the input circuit of the second, a source of signal energy, means for connecting said source to the input circuit of the first tube, a utilizing device connected to the output of the second tube, means for feeding back energy derived from the output of the second tube to the 20 input of the first tube in a positive sense to thereby produce regeneration, a source of quenching 25 oscillations and coupling means between the source of quenching oscillations and each of said tubes for applying oscillations from said source to both said tubes simultaneously.

WILLIAM SPENCER PERCIVAL.
